UNITED STATES PATENT OFFICE.

HENRY S. HALE, OF PHILADELPHIA, PENNSYLVANIA, ASSIGNOR TO THE
HALE AND KILBURN MANUFACTURING COMPANY, OF PHILADELPHIA,
PENNSYLVANIA, A CORPORATION OF PENNSYLVANIA.

CUSHION.

No. 854,161.

Specification of Letters Patent.

Patented May 21, 1907.

Application filed May 8, 1905. Serial No. 259,391.

To all whom it may concern:

Be it known that I, HENRY S. HALE, a citizen of the United States, residing at Philadelphia, in the county of Philadelphia and 5 State of Pennsylvania, have invented a certain new and useful Improvement in Cushions, of which the following is a specification.

The present invention includes both a new article of manufacture and a preferred embodiment thereof, both in the cushion art and adapted particularly for use in connection with upholstered seat- and back-cushions of the type employed in railway coaches and other articles of furniture generally.

15 Cushions of this sort commonly include a suitable frame, usually rectangular, supporting a series of coil-springs over which upholstery material is placed, the cushion being finished by a wearing surface of ratan, plush, 20 pantasote, etc. Such cushions are divisible broadly into two classes, in one of which, known as "spring-edge", a series of coil-springs underlie the upholstery and covering adjacent to the edges, so as to afford desired 25 elasticity, while in the other class such edge springs are omitted, the cushion cover, and in some cases the upholstery or canvas below such cushion cover, being secured to frame members of a height but little less than the 30 thickness of the seat intermediate of such members. The present invention is applicable to both these classes of cushions, but for convenience will be described in connection with a structure of the class first named.

35 In all such structures it has heretofore been the practice, in order to give a finished appearance to the edges of the cushion, to laboriously stitch through the textile material or upholstery or both, secured in position above 40 the springs, so as to form a bead extending entirely around the cushion or on the forward and rearward edges thereof. This operation has proved time-consuming, as is also the operation of applying the felt, curled hair 45 or other material, which for convenience I shall refer to herein broadly as "upholstery material".

My object is to provide, as a new article of manufacture, a novel form of material for 50 use in cushion-making, this comprising felt, hair or other upholstery material united by suitable means, such as glue, to a strip or band of textile material, such as canvas.

This may be made in any desired quantity and sections of suitable length cut for application to a cushion-frame. In preparing it for this use, I fold the strip of composite material longitudinally, either with or without the insertion at the fold of a cord or reed or similar structure, preferably round in cross-section, stitching the two sides together at a short distance from the fold, and, if such cord or reed be employed, around such cord or reed, using either one or more parallel rows of stitching. The composite material may 65 be applied to the cushion-frame in this form, the webs thereof beyond the bead formed by the stitching lying together and in parallel planes or being separated to permit its arrangement in angular position along the 70 cushion edges. Where the latter procedure is followed, one web of the material may be secured to a spring-member of the cushion-frame and the other web to a stationary 75 member of the cushion-frame, additional upholstery material being applied over the surface of the cushion to bring up the level thereof to the proper height and provide requisite softness. Over the structure so formed, the 80 wearing surface or cushion cover of plush, ratan or other material may be placed, its edges being tacked or otherwise secured either to the sides of the cushion or to the under surface thereof, a firm and uniform 85 appearance being given at the edge thereof by the underlying bead formed by the composite material as above described. If desired, such cover may readily be stitched to such bead, so as not only to secure the cover in place but also to add to its ornamental 90 appearance.

The invention is illustrated in the accompanying drawings, in which Figure 1 is a central longitudinal section illustrating my invention as applied to a cushion suitable for 95 use on a car-seat; Fig. 2 is a similar view, illustrating another form in which the invention may be employed; Fig. 3 is a similar view illustrating a modification; Fig. 4 is an enlarged perspective view of a short section 100 of the upholstery material and Fig. 5 is a detail view hereinafter to be explained.

Referring to these drawings, in which similar letters denote corresponding parts, A, A', 105 designate the two side members of a cushion-frame and B the cross-arms extending be-

tween and connecting the same, both said side members A, A', and cross-arms B supporting in this instance, arranged in rows both laterally and longitudinally, coil-springs b.

C designates sectional wooden slats of the character commonly in use, extending around all four sides of the cushion and overlying and secured to continuous wooden slats c, 10 which in turn overlie and are secured to narrow metallic straps c'.

c² designates one of a series of corrugated steel bands, each extending over a lateral series of coil-springs b, the upper ends whereof 15 are preferably secured to said bands, the ends of said bands underlying the steel straps c'.

D designates what is commonly known as the "first canvas", this being a sheet of textile material extending over the steel bands 20 c² and slats c. This may, as shown in Fig. 3, extend no farther than to the outer edges of said sectional slats C, or if desired it may project beyond the same as shown in Figs. 1 and 2, in order that it may be pulled down so as 25 to place the spring system under tension, and its edge tacked or otherwise secured to the side-members A, A', of the frame.

If desired, I may provide the sectional slats C with a convex molding of wood or 30 other suitable material secured to such slats near their outer edges by means of clenched tacks, as shown in Fig. 1.

The upholstery device above referred to is shown detached and on enlarged scale in Fig. 35 4, and applied and on smaller scale in the other figures. In the manufacture of this, bands F of any suitable length are preferably coated with glue, and while same is hot bands or sections of upholstery material, f, are applied to the adhesive surface under pressure, 40 so as to firmly unite therewith. Such band is then folded longitudinally, preferably around a central core f' of cord or ratan reed, and then stitched adjacent to the fold, 45 as at f², either one or more lines of stitching being employed, as desired. This material, being of such character as to permit it to be manufactured and carried in stock, may be applied to the cushion-frame as above de- 50 scribed in any suitable manner, the bead, however, formed by the fold of such material, projecting outwardly for coaction with the cushion-cover G. In Fig. 1, I have shown the two webs, f³, f⁴, as arranged in parallel planes, 55 the whole material being secured in position by means of nails f⁵ extending through said material and through first canvas D, slats C and c, and straps c', the ends of such nails being clenched on the under side of said strap. 60 Where this arrangement is observed, the surface of the cushion inside the marginal layer of upholstery material may be covered over with loose upholstery material g, sufficient thereof being employed to bring up the height 65 of the cushion as a whole to the desired point,

this point being preferably above the horizontal plane of the marginal bead above described. After this has been done, the wearing surface or cover of the cushion may be applied, as illustrated, the edges thereof being tacked or otherwise secured preferably to the under side of the side and end members of the cushion-frame. Also, if desired, said cover G may, as shown in Fig. 5, be stitched to the bead in such manner as to give such cushion 75 the appearance of being beaded also.

Instead of leaving the webs f³, f⁴, in parallel planes as shown in Fig. 1, I may, as shown in Fig. 2, separate the same, either employing the molding E or not as preferred, securing one of said webs to the slats overlying the edge series of coil-springs, as, for instance, by means of a clenched nail as above described, and allowing the other web, f⁴, to extend downwardly, in order that the edges of the 85 cushion may be upholstered as well as the top thereof. Or, if desired, the upholstery material of such web f⁴ may be removed as illustrated in Fig. 3, the edge of the canvas exterior of such web being tacked or otherwise secured to the frame. Where this construction (either involving or not involving removal of the upholstery material as just described) is employed, the spring system may be placed under the necessary tension 90 upon securing the canvas exterior of the web f⁴ to the frame, and the first canvas in such case may extend only over the steel bands c², and if desired over the sectional slats C, its function of placing the spring system under 100 tension being thus transferred to the web f⁴. These and other modifications of or departures from the preferred form of cushion construction illustrated in Fig. 1 will readily suggest themselves to the skilled mechanic and 105 may be made without departing from the spirit of the invention herein disclosed.

Having now described my invention, what I claim as new therein and desire to secure by Letters Patent is as follows:

1. As a new article of manufacture, a strip of textile fabric and elastic upholstery material secured to the surface thereof, said strip being folded longitudinally to bring together the faces on either side of said fold to which said upholstery material has been applied and to form a bead at the folded edge of said strip, substantially as set forth.

2. As a new article of manufacture, a strip of textile fabric and elastic upholstery material secured to the surface thereof, said strip being folded longitudinally to bring together the faces on either side of said fold to which said upholstery material has been applied, and a core lying within said fold at the bight thereof, substantially as set forth.

3. The combination of a cushion-frame, springs carried thereby, a covering overlying said springs and secured at its edges to said frame, an upholstery device extending 130

around the edges of said cushion and comprising a band of textile fabric and upholstery material secured to the surface thereof folded longitudinally, and means for securing 5 said device in position, substantially as set forth.

4. The combination of a cushion-frame, springs carried thereby, a covering overlying said springs and secured at its edges to said 10 frame, an upholstery device extending around the edges of said cushion and comprising a band of textile fabric and upholstery material secured to the surface thereof folded longitudinally and having the webs thereof 15 stitched together, and means for securing said device in position, substantially as set forth.

5. In a cushion, a base or frame, springs supported thereon, an auxiliary frame above 20 the main frame and supported thereon, an upholstery device overlying said auxiliary frame and comprising a strip of textile fabric and upholstery material secured to the surface thereof folded longitudinally, and a 25 covering overlying said upholstery device and secured at its edges to said frame, substantially as set forth.

6. In a cushion, a base or frame, springs supported thereon, an auxiliary frame above 30 the main frame and supported thereon, an upholstery device overlying said auxiliary frame and comprising a strip of textile fabric and upholstery material secured to the surface thereof folded longitudinally and having 35 the webs thereof stitched together, and a covering overlying said upholstery device and secured at its edges to said frame, substantially as set forth.

7. In a cushion, a base or frame, springs 40 secured thereon, an auxiliary frame above the main frame, springs supporting the auxiliary frame upon the main frame, an uphol-

sterly device comprising a strip of textile fabric and upholstery material secured to the surface thereof folded longitudinally, and 45 means securing said upholstery device upon said auxiliary frame, substantially as set forth.

8. The combination with a cushion-frame and springs carried thereby, of means for 50 placing said springs under tension, and an upholstery device extending around the edges of said cushion and comprising a band of textile fabric and upholstery material secured to the surface thereof folded longitudinally, said device being secured to said frame, substantially as set forth.

9. The combination with a cushion-frame and springs carried thereby, of means for placing said springs under tension, and an 60 upholstery device extending around the edges of said cushion and comprising a band of textile fabric folded longitudinally and upholstery material within the fold, the two webs formed by said longitudinal fold being 65 stitched together intermediate their lateral edges and said device being secured to said frame, substantially as set forth.

10. The combination with a cushion-frame and springs carried thereby, of means for 70 placing said springs under tension, and an upholstery device extending around the edges of said cushion and comprising a band of textile fabric folded longitudinally and upholstery material within the fold, said device having a central core and being stitched 75 adjacent to the fold and secured to said frame, substantially as set forth.

This specification signed and witnessed
this 2nd. day of May, 1905.
